(57) **CLAIM**

The ornamental design for an air filtration device, as shown and described.

DESCRIPTION

FIG. 1 is a top perspective view of an air filtration device in accordance with our new design;

FIG. 2 is a front elevational view thereof;

FIG. 3 is a top plan view thereof;

FIG. 4 is a bottom plan view thereof;

FIG. 5 is a left-side elevational view thereof, a right-side elevational view thereof being a mirror image; and,

FIG. 6 is a rear elevational view thereof.

The broken lines in the figures are for illustrative purposes only and form no part of the claimed design.
